STABILIZING MEANS FOR DOUBLE-WALL CONSTRUCTIONS

Basil G. Spencer, London, England, assignor to
 Bigelow-Liptak Corporation, Detroit, Mich., a
 corporation of Michigan

Application November 12, 1943, Serial No. 509,994

2 Claims. (Cl. 72—101)

The present invention relates to lining, facing, baffle or brickwork walls or jointed panelling, or the like building constructions (hereinafter referred to as a secondary-wall) adapted to be erected adjacent to, or spaced from, a main or primary-wall.

An object of the invention is to provide means for supporting such a secondary-wall in stable relationship to a primary-wall, even though the thinness of the secondary-wall is such that it would normally be unstable, and a further object is to supply such a secondary-wall which is unaffected by local movement or displacement, such for example as occasioned by expansion and contraction under considerable temperature changes likely to be met with under conditions which exist in furnace or heating chamber constructions.

It has been found in practice that lining or baffle walls, which are built up in the usual manner depending mainly on gravity for the stability, required to be substantially thick, which renders them subject to unequal expansion and contraction, due to their thickness, when subjected to differing temperature conditions throughout their mass, which may result in defective joints or instability.

One of the essential features of secondary lining or baffle walls for furnaces and the like is that they shall form an impervious screen to gases and consequently thick secondary-walls are to be avoided where gas-tightness is required and such walls should be made as thin as possible compatible with manufacturing practicability.

A further advantage of comparatively-thin secondary-walls is that they afford relatively little heat-storage capacity and consequently represent a saving of fuel and an increase of efficiency in starting up or making temperature changes.

The invention may be incorporated in refractory furnace-walls of the type known as "suspended-walls," formed of relatively-thick bricks or blocks suspended or detachably hooked or keyed upon a metal framework having horizontal members.

The invention relates to a secondary-wall adjacent to or spaced from a primary-wall in such a manner that the secondary-wall may be thin, by progressively stabilizing the secondary-wall by members extending from the primary-wall between the joints (preferably vertical joints) of the bricks or blocks of which the secondary-wall is composed, and having retaining abutment means adapted to engage the front and rear faces of such secondary bricks or blocks.

According to the invention each stabilizing member comprises a heat-resisting, flat metal-plate having at one end hook or other means for engaging the primary-wall or the framework of a suspended wall and having towards its other end a pair of abutment members projecting transversely at right-angles to the stabilizing plate member and spaced so as to engage the front and rear faces of the secondary-wall.

These stabilizing plate members are preferably slotted and have portions stamped or pressed up to afford lugs for detachably positioning the abutment plates, or at least one thereof, and for providing said hook or other securing means.

To enable those acquainted with this art to fully understand the invention and the advantages accruing from its employment, a present preferred embodiment thereof is illustrated in the accompanying drawings, forming a part of this specification and to which reference should be had in connection with the following detailed description.

In these drawings:

Figure 1 is a fragmentary, vertical sectional view through a furnace-wall embodying the invention, the novel stabilizing members being applied to a suspended furnace primary-wall of the character hereinbefore indicated, the upper portion of the figure being a section on line 1—1 of Figure 2 and the lower part of the figure being a section on line 1A—1A of Figure 2;

Figure 2 shows horizontal sections through the wall illustrated in Figure 1 on lines 2—2 and 2A—2A of such figure;

Figure 3 is a perspective view of one of the stabilizing-plates and its abutment-plates according to one form of the invention;

Figure 4 is a side-elevation of the structure illustrated in Figure 3; and

Figure 5 is an elevation of one of the abutment or plate members shown as extending at right-angles from the stabilizing-plate member presented in Figure 3.

In carrying the current invention into effect, according to one mode described by way of example as applied to a suspended, furnace primary-wall and in a manner adapted to provide a cavity or passage chamber between the primary and secondary walls, for the accommodation of pipes or tubes, the primary-wall is shown as comprising insulation-blocks 10, 10 hooked and keyed between horizontal, metal-frame members 11, 11 carried on vertical, supporting posts or channels 12, 12, of which only one is shown, by means of bolts 13, 13 which extend through apertures in

the metal-casing 14, such primary-wall also including intermediate insulation-blocks 15, 15 and an outer wall composed of insulation blocks 16.

Each horizontal, metal-frame member 11, of general channel cross-section, has a longitudinal, upstanding flange 17 along its outer part and a depending flange 18 along its inner part, flange 17 extending upwardly into a cavity 19 along the outer lower part of the corresponding blocks 10, flange 18 projecting downwardly into a slot 21 in the top of the corresponding or next lower blocks 10 intermediate between their inner and outer faces, the upper flange 17 conveniently constituting means for securing or holding in position the stabilizing-plate members to be described below.

The secondary-wall, illustrated in Figures 1 and 2, is composed of superposed, thin, building blocks, tiles or panels 22, 22, the upper and lower faces of which are formed or moulded with mortice and tenon or other keying or interengaging means 23.

The blocks or tiles 22 are erected to constitute the secondary-wall located in appropriate spaced relationship forwardly from the primary-wall block 10 and 15 so that an upright space or cavity 25 is provided within which pipes or tubes 26 for the conveyance of water or other liquid or air or gas to be heated, are accommodated.

Secondary-wall, relatively-thin, stabilizing members or plates 27 are provided, preferably apertured at 28 and 29 to reduce weight, and each of these comprises an inwardly-extended, flat metal-plate, as shown in Figure 4, formed from sheet-metal which at one end has been shaped and stamped to provide a longitudinal hook-member 31 having an extension 32 projecting laterally from the downwardly-directed portion of the hook, the corresponding end of plate 27 having a portion 33 projected therefrom laterally in the direction opposite to that of part 32.

Hook 31 and its transverse extension 32 are adapted to engage behind the flange 17 of the horizontal bar 11 (Fig. 1) while the portion 33 bridges the front face of the corresponding, horizontal, metal frame-member 11 as shown in Figures 1 and 2 lying against the edges of the two parallel flanges of the channel-member 11.

Near its opposite end, plate 27 has a pair of parallel slots 34, 35 extended downwardly from its upper edge and the plate is further cut and bent to provide two sets of four each of horizontal laterally-extended lugs, 36, 37, 38, and 39 and 41, 42, 43, and 44, alternate lugs of each set projecting in opposite directions from the vertical plane of the plate, one edge of all lugs of one set being in register with the corresponding edge of slot 34 and one edge of all of the lugs of the other set being in the register with the adjacent edge of the other slot 35, all as is clearly illustrated in Figure 4.

As is fully shown, the distance between the adjacent edges of the two groups of lugs is substantially the same as the thickness of the blocks or tiles 22 of the secondary-wall.

In addition, the portion of plate 27 between the two vertical spaced rows of lugs, has an opening 45 to accommodate the lateral keying or interengaging means 24 on the vertical edges of the blocks 22 (Fig. 2).

Each plate 27 is supplied with two abutment-plates 46 and 47, which may be alike, each having a central slot 48 (Fig. 5) of a width to accommodate the thickness of plate 27 and extending up-

wardly from its lower edge a distance corresponding to that from the lower end of either slot 34 or 35 to the bottom edge of plate 27.

To reduce the weight of such abutment-plates each has its opposite, vertical edges recessed at 49, 49.

When plate 46 is in slot 34, and plate 27 is in slot 48 as presented in Figure 3, it is backed up and maintained in proper position by engaging the edges of the plurality of registered projections 36, 37, 38 and 39, and also, when the companion plate 47 is in slot 35, it is sustained in position and bolstered up by contact with the edges of the other group of vertically-aligned lugs 41, 42, 43 and 44.

In erecting the primary and secondary walls, the blocks are fitted together and between each of the vertical joints of the secondary-wall and the appropriate joints of the primary-wall one of the plates 27 is introduced and hooked over the corresponding flange 17 as portrayed in Figure 1.

The abutment-plate 46 may be already in position on plate 27 to assist in bedding the added blocks 22 in position, and after the next blocks have been placed above those already in place, the abutment-plate 47 is slipped into position in front of the secondary-wall blocks.

From the foregoing it will be apparent that the secondary-wall blocks are definitely positioned and stabilized at their rear faces by the plate 46 and tied at their front faces by the abutment-plate 47.

The erection of the wall is continued with the insertion of the stabilizing plates 27 into vertical joints at each course of the secondary blocks and preferably in the region of the horizontal joints thereof.

It will be appreciated that, by reason of the planes of the plates 27 lying in the planes of the vertical joints of the blocks, the plates will not interfere with the vertical expansion and contraction of the respective walls and will be unaffected by such movements, while lateral expansion and contraction movements of the wall are accommodated by the transverse flexibility of the relatively-thin plates 27.

It will be realized that, by making the abutment-plates 46 and 47 and the plate 27 mutually slotted, either of the abutment-plates can be removed by sliding it vertically and this is particularly convenient in reference to the front plate 47 as it enables the plate to be detached so that the individual blocks 22 may be removed for replacement or repair from the secondary-wall, but although this arrangement is convenient, it will be understood that it is not essential that the plate 46 or 47 or both of them should be detachable.

For example, the plate 46 may be replaced by a plate welded in position, or the plate 27 may be stamped out with tongues which will afford supporting areas equivalent to the plate 46 on either side, or on both sides, of the plane of the plate 27.

According to a modification, the plate 27 may be formed with apertures through which wedges, split-pins or the like may be introduced to serve as abutment members.

Further the hook means 31 and 33 may be replaced by other means adapted to engage the framework of the primary-wall or engage the rear surface of the blocks or slots therein.

The stabilizing plates in normal circumstances may be constructed of very light metal and may

be as thin as $\frac{1}{8}$ " or less and the metal of which they are composed should be such as to have the necessary heat-resisting properties to withstand temperatures obtained in heater, drier or combustion chambers, for example, the metal employed for these plates may be nickel chrome steel.

By making the stabilizing-plates very thin, it will be appreciated that very little space in the cavity 25 is occupied thereby, enabling the vertical pipes or tubes 26 to be installed in as closely spaced relation as may be required, and further it will be understood that the thin plates offer no appreciable obstruction to the passage of any gases which may be caused to pass upwardly or downwardly in the space 25 for heating the tubes 26.

The longitudinal and transverse dimensions of the plates may be varied as desired and should be designed to accord with the position and purpose of the secondary-wall to afford a double-cavitated wall or a double wall in which the secondary-wall is adjacent to or contiguous to the primary-wall.

The blocks of the secondary-wall may be of the same material as those of the primary-wall or such may be of a different material according to requirements.

Thus, for instance, in the case of a lining for a furnace of the secondary-blocks may be of dense firebrick forming a protective-covering to the softer or insulating brickwork of the primary-wall.

I claim:

1. In a known type of double-wall construction having an upright framework including vertically-spaced horizontal-bars, an outer primary-wall mounted on and supported by said framework, an inner secondary-wall spaced inwardly from said primary-wall and having superimposed panels in the same plane, and means securing said secondary-wall to said framework, said securing means including the novel combination of a plurality of sheet-metal stabilizing-plates extending longitudinally inwardly from said framework, the outer end portion of each said stabilizing-plate having (a) a hook integral therewith to engage over one of said horizontal-bars, (b) a lateral extension on and integral with said hook bent out of the plane of said hook and

engaging the outer surface of said bar, (c) a plate integral with and bent out of the plane of said stabilizing-plate and bearing on the inner face of such bar and projecting from said stabilizing-plate in the direction opposite from said extension, (d) a first abutment-plate on, at a right-angle to the plane of, and projecting from both faces of, such stabilizing-plate and against which the outer surface of said secondary-wall bears, said stabilizing-plate having (e) lateral lugs integral with and bent out of its plane and backing up said abutment-plate, and (f) a second abutment-plate on, and at a right-angle to, the plane of, and demountable from, said stabilizing-plate and bearing against the inner surface of said secondary-wall.

2. A stabilizing-plate for use in a double-wall construction to stabilize a secondary-wall thereof spaced inwardly from a primary-wall thereof by engagement with the framework supporting the primary-wall, said stabilizing-plate embodying the novel improvements (a) that it is of sheet-metal, (b) that its primary-wall end portion has a hook adapted to engage a horizontal portion of said framework, (c) that said hook has a lateral extension bent out of the plane of the plate adapted to bear on the outer face of said horizontal portion of the framework, (d) that it has a lateral-plate bent out of the plane of the stabilizing-plate adapted to engage the inner face of said horizontal portion, (e) that said extension and lateral plate project in opposite directions from the plane of the stabilizing-plate, (f) that the secondary-wall portion of the stabilizing-plate has a pair of independent transverse abutment-plates spaced apart lengthwise the stabilizing-plate a distance substantially the same as the thickness of said secondary-wall and adapted to engage the opposite faces of the secondary-wall, said abutment-plates projecting outwardly from both faces of the stabilizing-plate, the innermost one of said abutment-plates being demountable from said stabilizing-plate by reason of a slotted connection therewith, and (g) that it has lateral lugs bent out of its plane in opposite directions and adapted to bear against and back up said abutment-plate nearest the hook-end of the stabilizing-plate.
